UNITED STATES PATENT OFFICE

WARD N. GERE, OF LIVERPOOL, NEW YORK, ASSIGNOR, BY MESNE ASSIGNMENTS, TO ECLIPSE TEXTILE DEVICES INCORPORATED, OF ELMIRA HEIGHTS, NEW YORK, A CORPORATION OF NEW YORK

MACHINE FOR DRYING RANDOM COLORED YARN ON THE CONE

Application filed September 21, 1926, Serial No. 136,809. Renewed April 16, 1930.

This invention relates to a method of and apparatus for drying yarn which has been partially colored on hollow perforated cones or cores by causing a coloring liquid to pass through the portions of the yarn registering with the perforations as shown in my pending applications Serial No. 66,533, filed November 3, 1925, and Serial No. 109,930, filed May 18, 1926, or by any other method where-
10 by the application of coloring matter to the yarn leaves the whole or portions of the mass of yarn in a more or less moistened or dampened condition.

The main object is to provide a simple, eco-
15 nomical and efficient method of and means for effecting a more expeditious drying of the moistened portions of the yarn on the cone or bore than has heretofore been practiced by passing heated air through the moistened portions of the yarn registering with the perforations in the core immediately following the coloring operation so that the dry spotted yarn may be knit or otherwise worked into a fabric within a relatively short time
20 25 after the coloring operation as compared with the time usually required for such purpose.

In other words, I have sought to expedite the drying of the yarn upon the same bobbin or spool upon which it has been previously colored.

Another object is to utilize the heat developed by the operation of the air feeding and forcing means for heating the air as it
30 35 is delivered by said means to the previously colored yarn.

A further object is to provide means whereby the perforated cores or bobbins upon which the yarn is wound may be conveniently and expeditiously placed upon and removed from the air delivery nozzle.

Another object is to provide the air delivery nozzles with valves or plugs adapted to contact with the inner walls of the perforated core for confining the delivery of the air within the perforated zones of the bobbin except as it is permitted to pass through said perforations and the portions of the yarn registering therewith.

Other objects and uses relating to specific

features of the invention will be brought out in the following description.

In the drawings:

Figure 1 is a top plan of one form of apparatus for carrying out the objects of this invention in which the air delivery nozzles radiate from upright pipes to which the heated air is supplied by a suitable air compressor.

Figure 2 is a front elevation, partly in section, of the apparatus shown in Figure 1.

Figure 3 is an enlarged horizontal sectional view taken on line 3—3, Figure 2.

Figure 4 is an enlarged transverse vertical sectional view of the air compressor and 65 adjacent portion of the pipe leading therefrom.

Figure 5 is an enlarged detail sectional view, partly in elevation, of one of the screw supporting heads carried by one of the air delivery nozzles for receiving and supporting a perforated core or bobbin upon which the yarn is wound when subjected to the drying operation.

Figure 6 is a top plan of a modified form 75 of yarn drying apparatus in which the delivery nozzles are mounted upon a circular pipe having radial branches communicating with a central supply pipe which, in turn, is connected directly to the outlet of the air 80 compressor.

Figure 7 is a vertical sectional view taken on line 7—7, Figure 6, with the yarn cones to be dried upon the several delivery nozzles.

The air compressor may be of any standard 85 rotary gear type having a case —A— provided with an air inlet —a— and an outlet pipe —a'—, said pump being also provided with a pair of co-operative air compressors —B— rotatably mounted within the case 90 —A— between the inlet and outlet —a'— for compressing the air admitted through the opening —a— and forcing it outwardly through the outlet —a'— in the manner well-known in this type of compressor.

The impellers —B— are mounted upon separate shafts —b— which are geared to each other by gears —b'—, one of said shafts being provided with a pulley —c— adapted 100

to be belted to any available source of power, not shown.

As illustrated, in Figures 1 and 2, the apparatus also comprises a horizontal header pipe —1— which is connected intermediate its ends to the outlet pipe —a— of the compressor case —A— and its outer ends closed by suitable plugs —2—.

Rising from the ends an intermediate portion of the header pipe —1— is a series of upright pipes which are closed at the top by caps —3'— and are each provided intermediate their lower and upper ends with a series of relatively smaller branch pipes or delivery nozzles —4— radiating therefrom in circumferentially spaced relation for receiving and supporting a corresponding number of perforated cores or bobbins —d— each carrying a mass of yarn —D— wound thereon.

Each of the delivery nozzles —4— is secured at one end to one of the upright pipes —3— for communication therewith and has its other end closed while its intermediate portion is provided with an annular enlargement or head —5— for receiving and supporting the perforated core —d— of the yarn cone —D— as shown more clearly in Figure 3.

Each delivery nozzle —4— is preferably made in two sections —4'— and —4" — arranged end to end and having their adjacent ends threaded externally and screwed into a central socket in the corresponding head —5— to facilitate the assembling of those parts and also to permit the use of heads of different sizes as may be required for different sized cores —d—, the section —4'— being tubular from end to end while the section —4" — is only partially tubular from the end adjacent the section —4'— and is provided with radial openings —6— leading from the interior of the hollow end adjacent the section —4'— and just at the inside of the head —5— and between said head and the free end of the section —4" — to permit the passage of heated air from the upright pipe —3— through the pipe section —4" — and thence into the adjacent hollow end of the section —4" — where it is free to pass through the branch openings —6— into the perforated core —d—.

The cores —d— are preferably conical, their larger ends being opened while the smaller ends are more or less closed by contraction, said cores being usually made of relatively stiff paper or cardboard and are provided intermediate their ends with radial apertures —d'— arranged at suitable intervals circumferentially and lengthwise of the core to permit the passage of air therethrough to the registering portions of the yarn wound thereon after the yarn has been colored by a suitable coloring liquid which is passed through the apertures and registering portions of the yarn.

As shown in Figure 5 each head —5— is provided with a conical periphery having a spiral thread —7— upon and with which the larger end of the conical core —d— is adapted to be mounted and engaged with a turning or screwing motion so as to firmly hold the core on the nozzle while the heated air under pressure is being forced into the interior of the core and outwardly through the perforations —d'— and registering portions 75 of the yarn.

The nozzle section —4" — extends some distance beyond the corresponding head —5— so as to project a corresponding distance into the interior of the core —d— when the latter 80 is placed upon the head —5— or nozzle —4—, the inner of said section —4'— being provided with a valve or plug —8— adapted to engage the inner walls of the core at or near the small end thereof and some distance 85 from the head —5— to prevent escape of the heated air through the smaller end of the core in case it should be more or less open and thereby confining the heated air between said valve or plug and the head —5— except 90 as it is permitted to escape from the passages —6— through the apertures —d'— and thence through the registering portions of the yarn —D—.

The nozzles —4— of each upright pipe 95 —3— radiate therefrom at an angle of substantially 90 degrees so as to permit at least two vertical rows of yarn cones to be mounted thereon for drying at the same time, it being understood that a corresponding number 100 of yarn cones will be mounted upon the nozzles of each upright pipe thus permitting a simultaneous drying of a large number of previously colored yarn cones.

In Figures 6 and 7 the nozzles —4— are 105 secured to a circular pipe —3'— so as to radiate therefrom preferably in outwardly and upwardly inclined planes at regular intervals throughout the circumference of the pipe —3'—.

This circular pipe —3'— is connected by inwardly extending radial branches —1'— to the discharge pipe —a'— of the pump case —A— whereby the air which is heated in and discharged from the pump is forced 115 through the branch pipes —1'— and thence into the circular pipe —3'— from which it is delivered through the nozzles —4— into the corresponding perforated cores and thence outwardly through the perforations —d'— and registering portions of the yarn —D—.

The perforated cores —d— with the yarn thereon are mounted upon the nozzles —4— on the pipe ring —3'— in substantially the 120 same manner as previously described for the nozzles —4— on the upright pipes —3— while the nozzles on the ring —3'— are arranged circumferentially uniform distances apart sufficient to permit the yarn cones to be 130

easily placed thereon and removed therefrom when desired.

Operation

- 5 The perforated cores —d— with the previously colored and more or less moistened yarn thereon are placed upon the several nozzles —4— or rather upon their respective heads —5— whereupon the action of the 70 pumps of the rotary members —B— of the pump draws the fresh air into the pump case —A— and heats the air to a pre-determined degree by reason of the compression thereof, said heated air being then delivered through 75 10 the corresponding pipe system and thence into the several nozzles —4— from which it passes through the perforations —d'— and outwardly through the registering portions of the yarn —D— thereby effecting a quick 80 15 drying of the previously colored portions of the yarn, the time required for complete drying of the colored portions of the yarn being dependent somewhat upon the temperature of the air delivery to the nozzles by the pump 85 20 25 —A—.

Care must be taken however to keep the temperature of the air sufficiently low to prevent burning or charring of the yarn and paper core upon which it is wound.

- 30 Otherwise the operation will be clearly understood from the foregoing description taken in connection with the accompanying drawings.

It will be observed that the outer end faces 35 of the threads —7— are more abrupt than the inner faces for effecting a firmer grip upon the paper cones when screwed thereon.

What I claim is:

1. In an apparatus for drying yarn on a 40 perforated conical core which is open at its larger end, a frusto-conical plug for the larger end of the core and means for passing air through said plug to the interior of the perforated core and thence outwardly 45 through the perforations and through the 100 105 yarn.

2. In an apparatus for drying yarn on a perforated conical core which is open at its larger end, a rod extending into the core 50 through its larger end and containing a central air passage and radial openings therefrom within the core, and a frusto-conical plug fixed on said rod and closing the larger end of the core.

- 55 3. In an apparatus for drying yarn on a perforated conical core whose larger end is open, a rod extending into the core through its larger end and containing a central air passage and radial openings therefrom within 60 the core, and plugs fixed on said rod at opposite sides of said radial openings for closing the larger and smaller ends of the core.

4. A holder for a cone of yarn, comprising 65 a frusto-conical mandrel having a sharp

projecting screw thread whose surface facing toward the larger end of the mandrel is perpendicular to the axis of the mandrel and whose other surface is inclined, so that the screw thread takes a firm grip on the interior of the cone and draws it upon the mandrel on relative rotation of the mandrel and the cone.

5. In an apparatus for drying yarn wound on a perforated conical core which is open at its larger end, a frusto-conical plug for the larger end of the core, a screw thread having spaced turns projecting from the frusto-conical surface of the plug and adapted to draw the inner surface of the core tightly against the frusto-conical surface of the plug on relative rotation of the core and plug, and means for passing air through said plug into the interior of the perforated core and thence outwardly through the perforations and through the yarn.

6. In an apparatus for drying yarn wound on a perforated conical core which is open at its larger end, a frusto-conical plug having a sharp projecting screw thread whose surface facing toward the larger end of the plug is perpendicular to the axis of the plug and whose other surface is inclined so that the screw thread takes a firm grip on the interior of the core and draws it tightly against the plug on relative rotation of the plug and core, and means for passing air through said plug into the interior of the perforated core and thence outwardly through the perforations and through the 95 100 105 110 115 120 125 yarn.

In witness whereof I have hereunto set my hand this 16th day of September, 1926.

WARD N. GERE.
